DRILLING, PUNCHING, AND MORTISING
MACHINE

Hermann J. Kaiser, Harper, Tex.

Application December 9, 1937, Serial No. 178,870

3 Claims. (Cl. 29—26)

This invention relates to combination drill, punching and mortising machines, and has for its main object the provision of such a machine which is simple in construction and efficient and economical in operation. A worker using the machine can quickly change it over from one of its functions to another, so that a minimum amount of time is lost, and the machine results in a great increase in productive efficiency.

The above and other objects will become apparent in the description below, in which characters of reference refer to like-named parts in the accompany drawing, forming a part hereof.

Referring briefly to the drawing, Figure 1 is a front elevational view of the machine.

Figure 2 is a cross-sectional view taken on the line 2—2 of Figure 1.

Figure 3 is a cross-sectional view taken on the line 3—3 of Figure 1.

Figure 4 is a cross-sectional view taken on the line 4—4 of Figure 1.

Referring in detail to the drawing, the numeral 10 represents a standard composed of a pair of spaced apart uprights 11 and 12 joined at the top by a cross piece 13. The uprights 11 and 12 are formed of channel irons having their channels juxtaposed, and likewise the cross-piece 13 is formed of a channel iron, with its channel facing downward. A table 15 is mounted between brackets 17 secured to the standard 10 and legs 16 at a distance therefrom, and a table apron 18 is supported within the uprights 11 and 12 by a channel iron cross-member 19. The legs 16 are braced near the bottom by a member 14.

Coiled springs 20 depend from the cross-piece 13 and support a hollow slide bar 21 whose extremities are slidable in the channels of the uprights 11 and 12. Bent rods 22 are attached to the bar 21 and hang therefrom, the lower ends thereof being secured to the extremities of a cross-arm 23. A rod 24 extends centrally from the latter and is pivoted to a foot lever 25 which in turn is pivotally attached to the brace 14. It is obvious that depression of the pedal 25 will draw the bar 21 downward, and release of the pressure will permit the springs 20 to raise the bar.

A platform 26 is supported on brackets 27 within the width of the uprights 11 and 12 and between the same. A hand wheel 28 has its shaft 29 extending through the upright 11 and a bevel gear 30 is on the end of this shaft. The gear 30 engages a bevel gear 31 on the end of a shaft 32 which extends upward through the platform 26 and through a second platform 33 above the first

platform. A gear 34 is rigid on the shaft 32 flush against the platform 26.

A vertical rack 35 is secured at its upper end to the cross-piece 13 and at its lower end 36 (extending at right-angles) on the platform 33. A shaft 37 extends slidably through aligned openings in the end 36 of the rack and the platform 33, the lower end of the shaft continuing through a similar opening in the platform 26 and having at its extremity a socket into which a screw 38 projects. The socket is adapted to have various tools interchangeably locked therein by the screw 38.

The upper end of the shaft 37 is rotatably secured, with the use of ball bearings, to the hollow split bar 21 whose two sides are united by bolts 39. A rack pinion 40, in mesh with the rack 35, is retained thereagainst by a sliding strap 41, and arms 42 which depend rigidly from the strap 41 are rigid with the top of the bar 21. A crank 43 is rotatable on shaft 44 of the pinion 40, and the pinion 40 has a ratchet wheel 45 rigid on the side thereof and engaged by the pawl 46 of the crank 43. The ratchet and pawl construction and the spring-controlled pawl of the crank are all of standard construction and their mode of operation is apparent. The crank 43, when inoperative, may be held in raised position by a stiff wire hook 53. It is also obvious that, when the crank 43 is rotated in a clockwise direction Figure 2, the shaft 37 will be carried downward. The shaft 37 is provided with a keyway 47 through a length normally lying between the platforms 26 and 33. A gear 48 loosely surrounds the shaft 37 just above the platform 26. This gear has a rigid collar 49 having a radial opening therethrough, through which a pin 50 slidably projects. A winged member 50 is secured about the pin 51, and on the ends of this member the ends of a coiled spring 54, which is looped around the collar 49, are attached. The spring 54 is in frictional contact with the peripheral surface of the collar 49. It is thus obvious that the pin 50 is normally urged toward the center of the collar. When the pin 50 lies in the keyway 47 of the shaft 37, the shaft 37 will rotate with the gear 48. To unlock the gear 48 from the shaft 37, the pin 50 is simply extracted by hand and the keyway is moved to one side of the pin 50 by turning the hand wheel 28 through a small arc.

To use the device as a drill, the crank 43 is worked to bring the shaft 37 downward until the drill 52 is at the desired level near the table 15, with the pin 50 registering in the keyway 47 of the shaft 37. The hand wheel 28 is then turned.

The operation of mortising or gouging out is performed in the same manner, with the substitution of the proper tool for the drill 52. When it is desired to do punching, a punch is substituted 5 for the drill 52 and the punch is brought down against and raised from the work on the table by operating the pedal 25, whence the punching can be accomplished at a fast rate.

It is thus apparent that an efficient and practical machine has been devised for the purposes mentioned, which can be quickly changed over from use for one operation to another. Obviously, modifications in form and structure may be made without departing from the spirit and scope of 15 the invention.

I claim:

1. A machine of the class described comprising an upright frame having a pair of spaced apart sides and a top, a cross bar slidably mounted between said sides, springs normally urging said bar toward said top, a table mounted between said sides, and upper platform and a lower platform secured to said sides intermediate said table and said top, a vertical shaft depending from said bar and having its upper end rotatably supported therein, said shaft passing loosely through said platform, a pinion rotatably mounted on said bar, a vertical rack extending between said top and said upper platform, said pinion engaging said rack, crank means for rotating said pinion to raise or lower said bar and shaft, a gear loose on said shaft and flush against said lower platform, said shaft having a keyway between said platforms, a rigid collar on said gear having a radial opening therethrough, a pin slidably mounted in said opening against said shaft, a hand wheel mounted on said frame, and means for rotating said gear upon rotation of said hand wheel.
2. A machine of the class described comprising an upright frame having a pair of spaced apart sides and a top, a cross bar slidably mounted between said sides, springs normally urging said bar toward said top, a table mounted between said sides, and upper platform and lower platform secured to said sides intermediate said table and said top, a vertical shaft depending from said bar and having its upper end rotatably supported

therein, said shaft passing through said platforms, a pinion rotatably mounted on said bar, a vertical rack extending between said top and said upper platform, said pinion engaging said rack, crank means for rotating said pinion to raise or lower said bar and shaft, a gear loose on said shaft and flush against said lower platform, said shaft having a keyway between said platforms, a rigid collar on said gear having a radial opening therethrough, a pin slidably mounted in said opening, resilient means normally urging said pin through said opening against said shaft, a hand wheel mounted on said frame, and means for rotating said gear upon rotation of said hand wheel, a cross-member suspended from said bar lying near the bottom of said frame, a foot pedal rotatably mounted near the bottom of said frame and having means connected with said cross-member for lowering said cross-member upon depression of said pedal.

3. A machine of the class described comprising an upright frame having a pair of spaced apart sides and a top, a cross bar slidably mounted between said sides, springs normally urging said bar toward said top, a table mounted between said sides, and upper platforms and a lower platform secured to said sides intermediate said table and said top, a vertical shaft depending from said bar and having its upper end rotatably supported therein, said shaft passing loosely through said platforms, a pinion rotatably mounted on said bar, a vertical rack extending between said top and said upper platform, said pinion engaging said rack, crank means for rotating said pinion to raise or lower said bar and shaft, a gear loose on said shaft and flush against said lower platform, said shaft having a keyway between said platforms, a rigid collar on said gear having a radial opening therethrough, a pin slidably mounted in said opening against said shaft, a hand wheel mounted on said frame, and means for rotating said gear upon rotation of said hand wheel, the lower extremity of said shaft having a socket therein and means for releasably locking a tool in said socket.

HERMANN J. KAISER.
